FOREIGN PATENT DOCUMENTS

JP 1001524 S 1/1998

Primary Examiner—Gary D. Watson

Assistant Examiner—T. Chase Nelson

(74) Attorney, Agent, or Firm—Morgan, Lewis & Bockius LLP

CLAIM

The ornamental design for a portable fastening machine, as shown and described.

DESCRIPTION

FIG. 1 is a perspective view of front and left side of a portable fastening machine showing our new design of the preferred embodiment;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.
